(57) **CLAIM**

The ornamental design for a foot switch for an X-ray imaging diagnosis apparatus, as shown and described.

DESCRIPTION

FIG. 1 is a front perspective view of a first embodiment of a foot switch for an X-ray imaging diagnosis apparatus showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a front perspective view of a second embodiment of a foot switch for an X-ray imaging diagnosis apparatus showing our new design;

FIG. 10 is a rear perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side elevational view thereof; and,

FIG. 16 is a right side elevational view thereof.
